UNITED STATES PATENT OFFICE.

CHRISTIAN STATTMANN, OF CHICAGO, ILLINOIS.

DESIGN FOR A MUFF.

Specification forming part of Design No. 10,617, dated April 2, 1878; application filed February 28, 1878.
[Term of patent 3½ years.]

To all whom it may concern:

Be it known that I, CHRISTIAN STATTMANN, of Chicago, in the county of Cook and State of Illinois, have originated a new Design for Ladies' Muffs, of which the following is a full, clear, and exact description, reference being had to the accompanying photographic illustration, making part of this specification.

The nature of my invention relates to the shape of a fur muff or pocket, as worn by ladies for protecting their hands during cold weather; and it consists in shaping the fur covering so that it will present annular half-round hoops on the exterior face of the muff.

A is the exterior or fur portion of the muff, shaped so that it will represent a series of half-round hoops, a a, which are formed by stretching the wet fur skin over a wooden block of conforming shape. B is the lining, and C are the tassels. The hoops thus formed are, on their inside, filled out with hair and cotton, so that they will retain their shape.

What I claim as my invention is—

A design for a muff, composed of the exterior series of convex rings a, substantially as described and shown.

CHRISTIAN STATTMANN.
